corporation of Switzerland

Application July 21, 1939, Serial No. 285,659
In Switzerland July 29, 1938

1 Claim. (Cl. 171—264)

The present invention relates to induction watthour meters and more particularly to a novel and improved temperature compensated watthour meter.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

The single figure of the drawing shows a perspective view of an illustrative embodiment of the invention as applied to the potential core of an induction watthour meter.

The present invention has for its object the provision of a novel and improved induction meter of the Ferraris type which is provided with temperature compensating means in the shunt circuit of one of the core parts.

For the compensation of the temperature error of induction meters, there have already been employed among others a suitable temperature coefficient alloy arranged on the meter moving system, the permeability of which varies with the temperature.

The invention relates to an induction meter, which likewise makes use of a suitable temperature coefficient alloy for the compensation of the temperature error. According to the invention a shunt path of the driving system contains at least in part an alloy with a positive temperature coefficient, that is to say, an alloy, the permeability of which increased with an increase in temperature. In such arrangement, for example, either the shunt limb of the potential core may consist wholly or partially of an alloy of the kind above mentioned or the air gap between the shunt limb and the return yoke may be bridged by a

part formed of the alloy. The alloy can furthermore be also arranged in a shunt path of the current core.

It will be understood that the foregoing general description and the following detailed description as well, are exemplary and explanatory of the invention but are not restrictive thereof.

The driving system of the Ferraris meter comprises a potential core 1 and a current core 2. A plate of an alloy 3 with a positive temperature coefficient is arranged in the air gap formed by the shunt limb 4 and the return yoke 5. The plate of a suitable temperature coefficient alloy can be secured by clamping or in any other suitable manner to the potential core. The alloy can obviously replace some of the plates of the laminated shunt limb.

In order to compensate the temperature error of the meter to a large extent, the potential driving flux must of course decrease when the temperature rises and the phase angle between the current and potential fluxes must increase. This result is attained in the following manner: As soon as the temperature rises, the permeability of the alloy arranged in the shunt thereby becomes increased, permits correspondingly more lines of force of the potential flux to pass through the shunt path. Consequently, with a rise of temperature any increase in the turning moment and any reduction of the phase angle between the two moving fluxes is prevented.

The invention in its broader aspects is not limited to the specific mechanisms shown and described but departures may be made therefrom within the scope of the accompanying claim without departing from the principles of the invention and without sacrificing its chief advantages.

What I claim is:

A temperature compensated induction meter including a current core, a voltage core having a shunt limb adjacent a return yoke, and a thermally sensitive alloy having a positive temperature coefficient forming part of the shunt path and filling the gap between the shunt limb and return yoke.

AUGUST HUNGERBÜHLER.
